UNITED STATES PATENT OFFICE.

JAMES H. WAGENHORST, OF AKRON, OHIO.

ELECTRIC BLUE-PRINTING MACHINE.

1,383,352.

Specification of Letters Patent. Patented July 5, 1921.

Application filed June 21, 1916. Serial No. 104,984.

To all whom it may concern:

Be it known that I, JAMES H. WAGENHORST, a citizen of the United States, residing at Akron, in the county of Summit and State 5 of Ohio, have invented new and useful Electric Blue-Printing Machines, of which the following is a specification.

This invention relates generally to electric blue printing machines and more particularly to a continuous printing machine of the horizontal type, that is a type in which the transparent printing means is arranged horizontally, and the tracing and printing papers can be passed through in a continuous run, 10 thereby overcoming the disadvantage of the ordinary vertical type of machine which is capable of making prints at a maximum co-extensive with the size of the cylinder.

One object of the invention is to construct 20 a machine of the kind described in which a minimum number of arc lamps can be employed, and in which a Cooper-Hewitt lamp can be employed if desired.

Another object of the invention is to provide 25 a printing machine of this class which entirely avoids the use of a curtain, and another object is to provide a machine in which reflectors can be used in connection with the arc lamps thereby utilizing all possible rays 30 of light for printing purposes.

Another object of the invention is to provide 35 for carrying off the heat generated by the electric lamps and another object is to provide for the rapid drying of the washed print after the printing process has been completed.

It is also an object of the invention to provide a machine in which the tracing cloth and blue print paper can be fed through the 40 machine without slipping, and at the desired speed, and preferably by a step by step movement of predetermined extent or magnitude.

With these various objects in view the invention consists in the employment of a section 45 of a glass cylinder arranged horizontally and having a roll arranged opposite said glass and adapted to contact with the concave face thereof, together with means for rotating said roll and whereby the tracing cloth and printing paper are caused to pass between said roll and glass, and one or more electric lamps arranged opposite the convex face of said glass and spaced therefrom the requisite distance.

The invention consists also in means for 55 regulating the pressure upon the roll and

also the rate of rotation; and the invention consists also in arranging one or more reflectors in connection with the electric lamps and in providing a fan operated from the main drive for the purpose of carrying away the heat generated by the lamps and capable also of drying or assisting in drying the washed print after the printing operation has been completed.

The invention consists also in certain details of construction and novelties of combination hereinafter fully described and pointed out in the claims.

In the drawings forming a part of this specification,

Figure 1, is a side view of an electric blue printing machine embodying my invention.

Fig. 2, is a section on line 2—2 of Fig. 1.

Fig. 3, shows a slight modification.

Fig. 4, is a section on line 4—4 of Fig. 3.

In carrying out my invention I employ a frame comprising the uprights A, and foot pieces B suitably braced and connected. A roll or cylinder C, is mounted between the uprights A, the shaft or axis of said roll or cylinder extending through the uprights, the openings in the uprights for the passage of the cylinder axle or shaft are elongated as shown at A' instead of being round, so that the roll C can be adjusted transversely with reference to the uprights, this being accomplished by means of pivoted hanger arms D, pivoted to the uprights at D' and carrying the roll shaft at their lower ends, the upper ends having the rods E connected thereto which rods work through an apertured plate E' fastened to the upright and the outer end of this rod is surrounded by a spring F against which is fastened the winged nut F' screwed upon the threaded end of the rod E by means of which the desired tension or pressure is placed upon the roll C through the medium of the pivoted hanger D.

A curved glass G is securely supported in the frame and directly opposite the roll C and this glass G is curved upon the same arc as the roll C as shown so that the surface of the roll C can contact snugly and properly with the concaved face of the glass, the roll being covered with felt or other suitable material.

The upper end of the glass is spread slightly as shown at G', and the lower edge is similarly spread as shown at G'', thereby providing a V-shaped space on the upper side of roll for the introduction of the print.

ing material and upon the lower side of the roll a similar space is provided to permit the discharge of the printing material.

By the term printing material it will be understood that the tracing cloth and blue print paper is meant but it will be understood that this machine can also be used in connection with any form of negative, and printing paper. A suitable trough H, is attached to the frame upon the forward side and is intended to receive and hold the printing material, the ends of the printing material being first inserted into the upper tapering recess and gripped between the roll and curved surface of the glass, and the roll being held in close contact with the glass will carry the printing material around in the direction indicated when the roll is turned.

10 The roll is preferably turned step by step thereby permitting the printing material to be exposed for a predetermined time while it is held perfectly still, and this step by step movement of the roll is accomplished by placing a ratchet wheel I upon one end of the roll shaft or axle and also a rocking arm K which carries a pawl L which engages the ratchet wheel I. The arm K is rocked up and down by means of a pitman M slidably connected to the reduced end of the arm K as most clearly shown and at its lower end is connected to a worm gear N, operated by a worm O, mounted upon one end of the motor shaft P, and it will be understood 25 that the motor being in constant rotation will cause the gear N to rotate, which through the pitman M will rock the arm K which carrying the pawl engages the ratchet wheel and turns the roll around step by step, each 30 upward movement of the arm serving to feed the printing material around between the roll and glass, and by adjusting the connection between the pitman and arm K the rate of feed can be regulated as the part can be 35 adjusted so as to move a distance of one tooth, two teeth, three teeth, or four teeth as desired. After the printing material is passed around between the roll and glass it is discharged into a second trough H', and 40 if desired provision can be made for separating the negative and print so that the print only is received in this trough H' and the washing liquid can be contained in this trough if it is desired to wash the print 45 immediately after it is discharged from the printing cylinder.

The printing operation is accomplished by means of arc lamps Q, there being four such lamps shown in the present instance, but 50 it will of course be understood that the number of lamps employed and likewise the type of lamp will depend to a certain extent upon the nature of the work required, but I have found that by means of reflectors and the proper positioning of arc 55

lamps I am able to get a print of uniform exposure or uniform development and thereby cut down the amount of current by one-third as compared with the cylindrical type of electric blue printing machines.

70 In the cylindrical type of machine in which a lamp was employed having the current supplied to the lower carbon holder there was a tendency for the arc to blow, and this was objectionable as the carbon 75 would cast a shadow on one side and therefore, under expose the paper at that point.

This type of arc lamp however, has particular advantage in connection with the horizontal type of printer such as we are 80 now describing, and where only a section of the direct rays of light can be used instead of the complete circle of light as in the vertical type of machine. This blowing of the arc blows the light in the direction 85 of the glass G, and therefore, increases the efficiency of the lamp.

In order to take advantage of all of the light rays I provide reflectors R, arranged at angles to the rear of the lamps as shown, 90 these reflectors being supported between side members attached to the main frame, and it will be understood that the arc lamps are suspended from brackets attached to the main frame, and provided with suitable 95 switches and rheostats for the control of the current.

If desired a rotary fan S can be arranged at one end of the reflector box and which is operated by an endless belt mounted upon 100 the opposite end of the motor shaft, the function of this fan being to remove the heated air as quickly as possible and prevent the same coming in contact with the glass, and furthermore, this heated air can be utilized 105 for drying the prints in case they are put into the bath immediately they come from the printing glass and roller.

The rheostats, switches, etc., are all in easy 110 reach of the operator and it will be understood that the machine can be operated in whole, or in part by cutting out some of the lamps. The fan motor can be operated separately from the lamps so that the fan 115 can be used as a drier independent of the printing operation of the machine.

As previously stated the printing material is fed in over the top of the roll and comes out under the bottom of roll, passing 120 around between the roll and concave face of the glass, and as the roll is moved step by step there will be frequent periods of rest for the printing material as it passes through the machine. This mode of operation is highly advantageous.

125 It will also be understood that the operation of the machine is continuous and consequently any length of print can be made and it will be noted that curtains or coverings of any kind are completely avoided, the entire 130

printing operation being made by the direct application of the light rays through the concavo-convex glass, the printing material being held firmly against the concaved face 5 by means of the felt covered roll which has a constant pressure and consequently holds and feeds the printing material in its proper position while passing through the machine. The felt covered roll can be adjusted as to 10 tension in order to accommodate varying thicknesses of printing material and its step by step movements can be regulated or adjusted according to the nature of the printing material being used it being well understood 15 that some papers require longer periods of exposure than others, and consequently the rate of passage through the machine must be regulated accordingly.

It will be seen therefore, that I provide 20 a simple, inexpensive, and efficient electric blue printing machine of the continuous and horizontal type capable of carrying out all of the objects hereinbefore referred to.

In Figs. 3 and 4 I show a modification in 25 which a strip of plate glass 10 is arranged between the uprights A, and in connection therewith an endless belt 11 of the full width of the machine is moved step by step by the rolls 12 and 13 around which it travels, one 30 of said rolls being connected with and op-

erated from the motor as already described. The materials pass between the glass and belt, and a roll 19 acts in conjunction with the roll 13 to direct the materials to trough H'. A flat presser plate 15 of suitable material holds the endless belt against the glass plate, this presser plate having slotted ends 16 attached to uprights A, and bow springs 17 bear against the presser plate at definite points, said bow springs being connected to a 40 bar 18 adjustably connected to the uprights. Lamps Q are arranged as previously described and also the reflectors R, and it will be noted that the reflecting surfaces are of such length and arranged at such angles that 45 the light rays are evenly distributed and projected in straight lines.

What I claim is:

The combination with a transparent medium, of a source of light upon one side 50 thereof and spaced therefrom, a flexible apron contacting with the opposite side of said medium, variable pressing means contacting with said apron, means for moving said apron step by step, and means for varying the distance of each step.

JAMES H. WAGENHORST.
